United States Patent Office

Des. 198,406
Patented June 9, 1964

198,406

JUG

Daniel H. Robbins and Edmund J. Pierce, Rochester,
N.Y., assignors to Photostat Corporation, Rochester,
N.Y.

Filed Aug. 23, 1962, Ser. No. 71,423

Term of patent 14 years

(Cl. D58—5)

FIG. 2

FIG. 1

FIG. 3

FIG. 1 is a front elevational view of a jug showing our new design;

FIG. 2 is a side elevational view thereof; the opposite side being a mirror image thereof; and

FIG. 3 is a top perspective view thereof.

The rear not shown is substantially plain except for the ribs as indicated in FIG. 2.

We claim:

The ornamental design for a jug, as shown and described.
